[57] CLAIM

The ornamental design for a support for a combined sensor and alarm unit for a wood stove pipe system, as shown.

DESCRIPTION

FIG. 1 is a perspective view of a combined sensor and alarm unit for a wood stove pipe system showing my new design, with the wire broken away in the center portion to indicate indeterminate length;

FIG. 2 is a rear view of the alarm housing portion thereof;

FIG. 3 is a top view thereof;

FIG. 4 is a bottom view thereof;

FIG. 5 is a left side view thereof;

FIG. 6 is a right side view thereof;

FIG. 7 is a front view of the sensor portion thereof;

FIG. 8 is a rear view thereof;

FIG. 9 is a top view thereof; and,

FIG. 10 is a bottom view thereof.
